Inventor:

Carleton Ellis

UNITED STATES PATENT OFFICE.

CARLETON ELLIS, OF MONTCLAIR, NEW JERSEY, ASSIGNOR, BY MESNE ASSIGNMENTS,
TO STANDARD DEVELOPMENT COMPANY, A CORPORATION OF DELAWARE.

APPARATUS FOR CRACKING OILS UNDER PRESSURE.

Original application filed October 4, 1913, Serial No. 793,377. Divided and this application filed November 26, 1920. Serial No. 426,502.

To all whom it may concern:

Be it known that I, CARLETON ELLIS, a citizen of the United States, and a resident of Montclair, in the county of Essex and State of New Jersey, have invented certain new and useful Improvements in Apparatus for Cracking Oils Under Pressure, of which the following is a specification.

The present invention relates to the manufacture of gasoline from heavier oils. It will be fully understood from the following description thereof, illustrated by the accompanying drawing, which shows somewhat diagrammatically and partially in section apparatus suitable for carrying the invention into effect.

In accordance with the present invention, the hydrocarbon material to be treated is first passed through a decomposer, which may suitably consist of a series of tubes placed in a furnace and adapted to be heated while the hydrocarbon material passes through them and is subjected to thermal decomposition during such travel. Of course, the length of the tubes, the velocity of travel of the hydrocarbon material and the temperature of the surrounding heating gases may be proportioned with respect to each other. A quantity of steam may be introduced into the decomposer along with the oil or oil vapors, the quantity of steam being such as to provide water up to 20-50%, more or less, based on the nature of the oil employed. After the hydrocarbon materials have passed through the decomposing tubes to which a strong heat is applied externally to bring them to decomposing temperature of 400 to 600° C. or so, they pass to a vessel or container well insulated to prevent loss of heat, in which container the heated hydrocarbon materials undergo further reaction with establishment of certain conditions which could not be secured satisfactorily in the decomposing tubes. From the vessel or container the products may pass into a dephlegmator or fractionating column, (not shown) which may be suitably arranged to yield as fractions a gas oil and unconverted kerosene, especially if the latter is employed as the raw material. Either or both of these products may be returned to the decomposing tubes if desired.

The lighter oils or volatile spirits are condensed in any suitable manner. The con-

densed product may, if desired, be redistilled or refined by means of sulfuric acid and alkali or subjected to any other method of treatment, although in general this is unnecessary when the products are passed through a hydrogenating device, such as is shown in the application of which this is a division.

Referring more particularly to the drawings, the numeral 1 indicates a furnace structure containing a battery of heating tubes as shown at 4. These tubes consist of pipes set horizontally or practically so, connected end to end in such manner as to form a continuous passage from the upper horizontal tubes to the lower ones. They are heated by any suitable means, for example, by fuel gas supplied through the pipes 2. A stack or chimney opening 3 for removal of the spent gases or products of combustion, is provided. A feed pipe 5 serves for the introduction of oil, oil vapors, oil and water, steam and oil, or the vapors of steam and oil. These pass downwardly through the several series of heating pipes and then by risers 6, are taken to the manifold 7 which communicates with the drum 8, which, as clearly indicated in the drawing, is of much greater diameter than the decomposing or heating tubes. The drum is preferably of considerable length with reference to its diameter and has an inlet for hydrocarbon material at one end and its outlet 9 preferably at the other end. The products of combustion from the heaters below the decomposing tubes pass up and around the drum and in some cases may add heat to it and in other cases serve more as an insulating blanket of heated air to prevent any substantial drop of temperature in the drum 8. The hydrocarbon material travels slowly through the drum so that further conversion may take place therein.

The outlet pipe, 9, leads to a suitable condenser or cooling device, 10, from which products are discharged through pipe, 11, trap 12, and valve 14. Gases separated at the trap 12 may be discharged through the valved pipe 15. Steam may be supplied to the system through pipe 16, provided with valve 17. Hydrocarbon material may be forced into the system under any desired pressure by pump 18.

When water is used in the decomposing

tubes and an excess is employed, this will appear later on condensation and suitable means should be provided for its removal. The apparatus may be run at a slight pressure or a considerable pressure, as several atmospheres may be employed if desired. This application is a division of my prior application, Serial No. 792,877, filed October 4, 1913.

10 What I claim is:—

1. In apparatus for the manufacture of gasoline by cracking a heavier oil, the combination of a housing and furnace setting equipped with a fire box, above said fire box 15 a nest of heating pipes united end to end to form a continuous, tortuous passage, a drum superposed above said pipes and connected therewith, the cross sectional area of said drum being relatively very much larger than 20 the cross sectional area of the heating pipes, a single outlet for said drum a cooler attached thereto, said cooler being provided at its discharge end with a valve, whereby 25 the entire apparatus may be maintained under pressure; and means for causing oil to pass through said heating pipes into said drum.

2. In apparatus for the manufacture of gasoline by cracking a heavier oil, the combination of a housing and furnace setting equipped with a fire box, a nest of heating pipes above said fire box, a collecting tank superposed above said pipes and connected therewith, the cross sectional area of said 30 collecting tank being relatively very much 35 larger than the cross sectional area of the

heating pipes, a single outlet for said tank, a cooler attached thereto, said cooler being provided at its discharge end with a valve whereby the entire apparatus may be maintained under pressure and means for causing oil to pass through said heating pipes into said collecting tank.

3. In apparatus for the manufacture of gasoline by cracking a heavier oil, the combination of a housing and a furnace setting providing a heating zone, a nest of heating pipes for heating oil to decomposing temperatures in said heating zone, means for causing oil to flow therethrough, a tank forming a collecting and digesting receptacle into which said pipes discharge, the cross sectional area of said tank being relatively very much larger than the cross sectional area of the heating pipes, a single outlet from the tank, means for cooling decomposed oil products, and means for maintaining the apparatus under superatmospheric pressure.

4. In apparatus for the manufacture of gasoline by cracking a heavier oil, the combination of the coil of pipes, means for forcing hydrocarbon oil therethrough, a digestion tank into which the coil discharges freely, said tank having a cross-sectional area much larger than the cross-sectional area of the pipes of the coil, the tank having a single outlet for converted products, means for supplying heat to the coils and for preventing substantial temperature drop in the tank, and means for maintaining the entire apparatus under super-atmospheric pressure.

CARLETON ELLIS.
